LOUIS C. GOAD AND FRANK D. WALSMITH, OF MUNCIE, INDIANA, ASSIGNEES TO
DELCO-REMY CORPORATION, OF MUNCIE, INDIANA, A CORPORATION OF DELA-
WARE

CASTING MACHINE

Application filed October 12, 1929. Serial No. 399,171.

This invention relates to machines for making castings in permanent molds and particularly for making castings from low melting point metal, such as lead.

One of the objects of the present invention is to provide a machine having a turn-table conveyor having passages through which a cooling medium may be circulated. In this connection a further object is to provide such a conveyor with detachable molds which may be removed from the conveyor with a minimum of labor and which when mounted upon the conveyor will be in good thermal contact therewith in order that heat may be dissipated readily from the molds through the walls of the conveyor through the cooling medium circulating through the conveyor.

A further object of the invention is to provide means for ejecting the castings formed in the molds which are detachably supported by the conveyor. This object is accomplished by attaching to each mold its own ejecting mechanism, all of the ejecting mechanism, of the molds being operated upon by a common operating member such as an annular cam concentric with the conveyor.

A further object is to provide automatic means for removing the castings from the conveyor after they have been ejected from the molds. In this connection it is a further object of the invention automatically to sort the various kinds of castings which are molded by the machine and to cause them to be moved into their respective receptacles.

Further objects and advantages of the present invention will be apparent from the following description, reference being had to the accompanying drawings wherein a preferred embodiment of one form of the present invention is clearly shown.

In the drawings:

Fig. 1 is a perspective view of the machine embodying the present invention.

Fig. 2 is a side elevation thereof, a portion of the base frame being broken away to show the drive mechanism.

Fig. 3 is a plan view of the machine.

Fig. 4 is a sectional view of an enlarged

scale taken substantially on the line 4—4 of Fig. 3.

Fig. 5 is a fragmentary side view of a part shown in Fig. 4 looking in the direction of the arrow 5 of Fig. 4.

Fig. 6 is a sectional view taken on the line 6—6 of Fig. 3.

Fig. 7 is a plan view partly in section of a portion of the conveyor, the section being taken on the line 7—7 of Fig. 6.

Fig. 8 is a fragmentary, developed, sectional view taken on the circle 8 indicated by dot-and-dash lines in Fig. 7.

Figs. 9 and 10 are fragmentary side elevations looking in the direction of arrows 9 and 10 in Fig. 3, these figures being drawn to a larger scale.

Referring to Figs. 2 and 6 the machine includes a base 20, supporting pedestals 21 which in turn support a platform 22. The base 20 and platform 22 are circular in peripheral contour and cooperate with arcuate plates 23 attached by screws 24 to the pedestals 21 to provide a hollow cylindrical housing for the driving mechanism of the machine. This mechanism comprises a motor 30 connected by coupling 31 with a shaft 32 which is journaled in suitable bearings provided by a gear housing 33 and which is connected with a worm 34 meshing with a worm gear 35 which is connected with a shaft 36 also journaled in bearings provided by the housing 33. The shaft 36 drives a gear 37 meshing with a gear 38 carried by shaft 39 which drives a gear 40 meshing with a gear 41, connected by a key 42 with a shaft 43 journaled in bearings 44 and 45 which is provided by a centrally located, cylindrical, hollow boss 46 integral with the platform 22. The shaft 43 is integral with a turn table conveyor frame 47, the weight of which is mainly supported by a ball thrust bearing 48, which comprises balls 49, an upper race 50 and a lower race 51.

Referring to Figs. 7 and 8, the conveyor frame 47 may be described as having a rim 52 which is connected with its hub or shaft 43 by three radial spokes 53 and by a web 54. The rim 52 provides three arcuate annular chambers 55 separated by approxi-

mately Z-shaped partitions 56. Water or other cooling medium is conducted into each chamber 55 through a pipe 57 and out of the chamber 55 through a pipe 58. The inlet and outlet pipes of any chamber are spaced apart an angular distance of 120°. This arrangement provides that an inlet pipe 57 of one chamber 55 is located beneath and in radial alignment with the outlet pipe 58 of an adjacent chamber 55. As seen in Fig. 8 the Z-shaped partitions 56 separate the inlet pipes 57 from the outlet pipes 58 which are located immediately above them. The pairs of pipes 57, 58 are used as inserts in the mold 15 in which the turn table frame 47 is cast. The material surrounding the pipes 57 and 58 provides the spokes 53.

The platform 22 supports pedestals 60 and 61 upon which rest the ends of a cross bar 62 which supports a central duct member 63 which extends through the hub 43 of the turn-table frame 47. The member 63 provides a water inlet passage 64 connected with a water inlet pipe 65 and at its upper 25 end with a side branch passage 66 leading into an annular distributing chamber 67 located between the hub 43 and the member 63 and provided by an annular groove in the hub 63. The chamber 67 communicates with the three inlet distributing pipes 57. The member 63 provides a central outlet passage 68 connected with a branch outlet passage 69 and with an outlet pipe 70. The branch passage 69 is connected with an annular 35 chamber 71 provided by the hub 43 and communicating with all of the outlet pipes 58. Water flows into the annular chambers 55 of the turn-table frame 47 through pipes 65, passages 64, 66, and 67 and thence through 40 the separate pipes 57 into the separate chambers 55 as indicated by arrows 57a in Fig. 8. The arrows 58a in Fig. 8 indicate that water flows out of the chambers 55 through the pipes 58. From the pipes 58 the water 45 passes into the annular passage 71 then out through the passages 69 and 68 and pipe 70. A nut 75 threaded upon the upper end of the member 63 engages the central tubular boss 76 of the cross frame 62 in order 50 that the central duct 63 may be supported by the cross frame.

The turn-table frame provides an annular ledge 80 upon which rests a turn-table ring 81, the inner cylindrical surface of 55 which very closely fits the contiguous cylindrical surface of the frame 47. This is necessary in order that there may be good thermal contact between the frame 47 and the ring 81. The ring 81 provides an annular 60 row of cavities which are oblong in contour and extend radially with respect to their longer dimension. Each cavity receives a mold block 82 providing a shoulder 83 which rests upon a similar ledge 84 provided by the ring 81. Each mold block 82 is secured into

position by one or more screws 85. The side surface of the mold block 82 above the shoulder 83 fits very closely the contiguous side walls of the mold block cavity in the ring 81. This is necessary in order to secure good 70 thermal contact between the mold block 82 and the ring 81.

Each mold block 82 carries its own ejector mechanism which comprises a frame 90 attached to the lower side of the mold block by 75 screws 91 and providing guides for the vertical sliding movement of a block 92 carrying a cross rod 93, the ends of which support rollers 94 which, as shown at the right hand side of Fig. 6, are adapted to engage ejector 80 cam plates or bars 95 provided by angle bars which have been bent into arcuate formation and which are attached to the platform 22 in such a manner that the bars 95 are concentric with the axis of the turn table. After the 85 metal has solidified in the mold block 82, its ejector mechanism will be operated to eject the casting. This is accomplished while the rollers 94 are riding up the inclined surfaces 95a of the cam plates 95 as shown in Figs. 1 90 and 10. As the rollers 94 move upwardly the block 92 moves upwardly and causes an ejector rod 96 connected therewith to move upwardly into the mold cavity of the block 82 in order to eject the casting. When the rollers 94 have moved away from the cam plates 95a a spring 97 will be released to cause the block 92 to move downwardly and ejector rod 96 to be retracted. Downward movement of the block 92 is limited by its striking a cross 100 bar member 98 provided by the bracket 90.

The turn table rotates in a clockwise direction as viewed from above or as shown in Figs. 1 and 3 or from right to left as viewed in Figs. 2, 9, and 10. Before a mold cavity is 105 filled with molten metal the ejector rods 96 will have been moved into the positions shown in Fig. 9. The metal is melted in a furnace, not shown, and is conducted through a pipe 100, shown in Fig. 1 which is kept at a 110 temperature above the freezing point of the metal by a stove 101 heated by a gas burner pipe 102. The metal is permitted to pass through a flow regulating valve 103 into a nozzle 104 whence the metal flows into a ladle 105 which is provided with trunnions 106 pivotally supported by brackets 107 attached to the cross frame 62. The ladle 105 normally rests in an upright position as shown in Fig. 110 9. In order that it may be dumped automatically so that it may discharge its contents at the proper time into a mold cavity located immediately beneath it, one of the trunnions of the ladle carries an arm 108 located in the 115 path of the pin 109 carried by a bracket 110 adjustably attached to the outer side of the conveyor ring 81 by screw 111. The ladle is provided with an anti-splash-apron 112 spaced from the metal containing vessel 113 130

so as to provide a relatively thin, wide passage 114 for the discharge of the metal.

The mold cavities are filled to overflowing. The excess metal is shown in Figs. 1 and 10 as being a flat cake of metal 120. The water which has been used to cool the side walls of the mold block 82 by passing through the chambers 55 of the turn table is permitted to flow past a valve 121 and through pipe 122, elbow 123 and pipe 124, whence it flows directly upon the cakes of metal 120 in order to hasten the cooling of the castings. The excess metal represented by the cakes 120 is removed by a scraper blade 125 which is adjustably supported on a bracket 126 attached by screws 127 to the cross frame member 62. The excess metal which is being removed is indicated by the peeling 128 in Fig. 10. These peelings are automatically removed from the conveyor due to the shape of the scraper blade 125 and fall into a suitable conveyor (not shown) which conveys them to the melting furnace. In order that the water discharged from the pipe 124 from the conveyor will not flow past the blade 125, the water is blown away from the blade 125 by jets of air issuing from a pipe 129 connected with a source of compressed air.

After the castings have solidified and the excess metal has been removed, as each mold block moves past the left of the cross frame 62 as viewed in Fig. 1, the casting ejector rollers 94 begin to ride up along the inclined surfaces 95a of the cam plates 95. By the time that a mold block 82 has moved into the position 82a in Fig. 1, a casting C will have been completely elevated above the mold and will then be engaged by a hook member 130 attached to the cross frame member 62. The function of the hook member 130 is to cause the casting to fall down immediately upon the top of the conveyor so that it will be in position to be ejected automatically from the table by being impinged upon by a jet of air issuing from one of a plurality of pipes 141, 142, 143, 144, and 145 which extend radially from an air manifold 146 connected with a source of compressed air by a pipe 147. The manifold 146 is attached to a bracket 148 by screws 149, and the bracket 148 to the cross frame member 62 by screws 150. The pipes 141, 142, 143, 144 and 145, are placed in communication with the manifold 146 respectively by valves 151, 152, 153, 154 and 155 which are open automatically at the proper time in the movement of the conveyor. Referring to Fig. 3 it will be seen that the machine has been arranged to mold five kinds of different castings and that the molds of each kind are arranged in pairs A1, A2, A3, A4, A5. The castings which are formed in the pairs of molds A1 to A5 respectively, are automatically caused to move from the turn table into chutes 161, 162, 163, 164, and 165. This is accomplished by attaching to the turn-table

frame 47 a plurality of radially extending blocks 166, each having a series of threaded holes 167 arranged in a radial row. Any one of the holes 167 may receive the threaded end 168 of a screw 169, the head of which is provided with a beveled camming surface 170 adapted to engage a button 171 attached to the lower end of a stem 172 of some one of the series of valves 151 to 155. It will be noted that these valves are located on centers corresponding in distances, respectively, from the axis of rotation from the turn-table, with the distances from the axis of the turn-table to the various holes 167. It is therefore apparent that by properly locating the screws 169 upon blocks 166 the various valves of the series 151 to 155 can be made to operate selectively. For example if it is desired that the castings ejected from the pair of molds A5 shall be automatically moved from the turn table into the chutes 165, then the screws 169 for operating the valve 155 which connects the pipe 145 with the air manifold 146 will be located in the positions 169^a shown in Fig. 3. It will be noted that the screws 169^a are in radial alignment with the mold cavities A5 and are the same distance from the axis of rotation of the turn table as the valve 155. Therefore when the castings which have fallen upon the turn table adjacent the mold cavities A5 have been rotated adjacent the pipe 145 the valve 155 will automatically open to cause a jet of air impinged upon the castings from molds A5 successively in order to blow these castings into the chute 165. In a similar manner the castings from molds A4 will be blown automatically into the chute 164, and the castings from molds A3 will be blown automatically by air from the pipe 143 into the chute 163; etc.

It is immaterial whether the mold cavities be arranged in pairs or whether any mold be alike or different from the one immediately adjacent to it. Obviously if the mold cavities are not arranged in pairs according to kind, but are different, then the various screws 169 may be arranged as shown in Fig. 1.

In order to brace the turn-table at a portion thereof adjacent the scraper blade 125, there is provided a bracket 180 attached by screws 181 to the platform 22 and supporting a roller 182 upon which the lower surface of the turn table ring 81 may rest. This feature is desirable in order that the blade 125 may operate uniformly in removing the excess metal.

While the form of embodiment of the present invention as herein disclosed, constitutes a preferred form, it is to be understood that other forms might be adopted, all coming within the scope of the claims which follow.

What is claimed is as follows:

1. A casting machine comprising, in com-

bination, a turn-table conveyor, blocks having mold cavities detachably supported by the conveyor, the walls of the blocks being in good thermal contact with the walls of the conveyor, and means for circulating a cooling medium through the conveyor in close proximity to said blocks.

2. A casting machine comprising, in combination, a turn-table conveyor having a central hollow hub, a rim provided with separate annular chambers, and ducts leading from this hub to the rim for conducting a cooling fluid to and from the chambers, and mold blocks attached to the conveyor and having their walls in good thermal connection with the walls of the chambers.
- 10 3. A casting machine comprising, in combination, a turn-table conveyor having annular chambers for receiving a cooling medium, means for circulating a cooling medium to and from said chambers, a ring supported by the conveyor at its periphery and having a wall in good thermal contact with walls of the chambers, and separate mold blocks received by recesses in the ring and having their walls in good thermal contact with the ring.

4. A casting machine comprising, in combination, a turn-table conveyor, blocks having mold cavities detachably secured to the conveyor, a casting ejector pin slidably supported by each block and removable with block from the conveyor, and a stationary arcuate cam concentric with the conveyor for 30 operating the rods.

5. A casting machine comprising, in combination, a turn-table conveyor provided with a plurality of mold cavities for making castings of different form, means for selectively ejecting the castings from the cavities and means for removing the castings from the conveyor.

- 40 6. A casting machine comprising, in combination, a turn-table conveyor provided with mold cavities, means for ejecting the castings from the cavities, a plurality of chutes each for a certain casting, and means for selectively removing the castings from the conveyor and for causing them to move 50 into their respective chutes.

7. A casting machine comprising, in combination, a turn-table conveyor provided with mold cavities, means for ejecting the castings from the cavities, a plurality of receptacles each for a certain casting, and means for selectively causing the various castings to move from the conveyor into their proper chutes.

8. A casting machine comprising, in combination, a turn-table conveyor provided with mold cavities, means for ejecting the castings from the cavities, a plurality of receptacles each for a certain casting, a plurality of air nozzles each located above the table and adjacent the entrance to one of the receptacles, valves located at different distances from the

axis of the table respectively for controlling the admission of air to the nozzles, and blocks attached to the table and having a radially disposed row of holes in alignment with a mold block, and means for operating an air valve and comprising a member adapted to be received by one of said holes.

9. A casting machine comprising, in combination, a turn-table conveyor provided with mold cavities, means for ejecting the castings from the cavities, a plurality of receptacles each for a certain casting, a plurality of air nozzles each located above the table and adjacent the entrance to one of the receptacles, valves located at different distances from the axis of the table respectively for controlling the admission of air to the nozzles, and devices for operating the valves each adapted to be attached to the conveyor adjacent a mold block, said devices being located at distances from the conveyor axis corresponding respectively to the distances from the conveyor axis to the respective valves which the devices are to operate.

10. A casting machine comprising in combination, a turn-table conveyor provided with a plurality of mold cavities of different form for making castings of different shapes, a plurality of receptacles each of which is adapted to receive castings of one particular type, and means for selectively ejecting the castings from the mold cavities, whereby castings of only one specific type are delivered into any one receptacle.

In testimony whereof we hereto affix our signatures.
